DESIGN FOR A SEWING RACK

Frank T. Olenick, Jr., Butte, Mont.

Application February 9, 1937, Serial No. 67,537

Term of patent 7 years

To all whom it may concern:

Be it known that I, Frank T. Olenick, Jr., a citizen of the United States, residing at Butte, in the county of Silver Bow and State of Montana, have invented a new, original, and ornamental Design for a Sewing Rack, of which the following is a specification, reference being had to the accompanying drawing, forming part thereof.

Figure 1 is a view in front elevation of a sewing rack, showing my new design.

Figure 2 is a view in side elevation thereof.

Figure 3 is a rear elevational view.

I claim:—

The ornamental design for a sewing rack as shown.
